BRASSIÈRE

Harry Gluckin, New York, N. Y., assignor to The
Gluckin Corporation, New York, N. Y., a cor-
poration of New York

Application November 19, 1945, Serial No. 629,574

7 Claims. (Cl. 2—42)

1

This invention relates to brassières and other garments employing breast supporting pockets or members with means for supporting such pockets upon the body of the wearer. More particularly, the invention deals with garments of the kind defined wherein a pair of pockets include a single brace or supporting frame encircling peripheral portions of the pockets and joined by a bridging member or loop disposed intermediate the pockets and spacing adjacent portions of the pockets. Still more particularly, the invention deals with the provision of means on the pockets for detachably supporting the frame unit therewith to facilitate laundering of the garment.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a front view of a brassière made according to my invention.

Fig. 2 is a rear view of the front central portion of the brassière made on an enlarged scale showing the means for retaining the supporting frame or yoke against displacement from the pockets, while permitting detachment of the frame therefrom.

Fig. 3 is a partial section on the line 3—3 of Fig. 2.

Fig. 4 is a partial section on the line 4—4 of Fig. 2; and

Fig. 5 is a plan view of the supporting frame or yoke detached.

In Fig. 1 of the drawing, I have shown, to illustrate one adaptation and use of my invention, a brassière having a pair of similar pockets 10 and 11. The pockets have lower curved edges 12 and 13 and upwardly extending contracted portions 14 and 15, to which adjustable shoulder straps 16 and 17 are secured. The side portions of the pockets 10 and 11 have substantially straight vertical edges 18 and 19, to which are attached side and back bands 20 and 21, the rear ends of which terminate in elastic straps 22 and 23, having means, as at 24, for detachably coupling the same at the back of the wearer. The shoulder straps 16 and 17 are attached to the bands 20 and 21, as at 25 and 26.

The pockets 10 and 11 may be of any desired construction and composed of one or two sheets of material, which preferably have darts, as at 27 and 28, to give the bust conforming contour to the pockets. Attached to part of the curved edges

2

12 and 13 of the pockets 10 and 11, and extending onto the side portions of the pockets to the side edge seams, as at 18 and 19, are bands 29 and 30 secured together in such manner as to form elongated channels 31 and 32, one of which is shown in cross-section in Fig. 3 and in partial longitudinal section in Fig. 4.

The straps or bands 29 and 30 have ends, as at 33, 34 and 35, 36, the ends 33, 34 being disposed at adjacent corner portions of the pockets 10 and 11; whereas the ends 35 and 36 terminate at the seam sides 18 and 19 at a point above the lower curved edges 12 and 13 of the pockets. Inwardly of and adjacent the ends 33, 34 of the channels 31 and 32 are formed openings 37 and 38. These openings are finished by turning the edges of the bands 29 and 30 inwardly, as seen at 39 and 40, in Fig. 4 of the drawing.

In Fig. 5 of the drawing I have shown, detached from the brassière, a supporting and reinforcing member or yoke 41, comprising two curved and substantially semi-circular portions 42, 43, inner adjacent portions of which are fashioned to form small loops 44 and 45 joining a large reversely curved loop or bridging portion 46 in offset shoulders 47 and 48, substantially in the manner illustrated in Fig. 5.

In attaching the member 41 to the pockets 10 and 11, the curved and substantially semi-circular portions 42 and 43 are inserted through the openings 37 and 38 and through the channels 31 to the ends 35 and 36 of the channels, at which time, the material of the pockets is extended along the curved portions 42, 43 sufficiently to pass the small loops 44 and 45 through the openings 37 and 38 to extend into the ends 33 and 34 of the channels, thus retaining the member 41 against accidental displacement from the pockets and leaving the bridge member 46 disposed adjacent edges of the pockets and spacing said edges one from the other. The yoke or large loop 46 provides a yieldable support between the pockets to adapt said pockets for spacing upon the breasts within predetermined limits.

In detaching the member 41 from the pockets, the above operation is reversed and the channel portions of the pockets are extended to forcibly detach the loops 44 and 45 through the openings 37 and 38, thus allowing the curved ends 42 and 43 to be readily withdrawn from the channels 31 and 32.

In the use of the garment, it will be apparent that the member 41 maintains the brassière or lower edge portions thereof firmly upon the body

of the wearer with the bridging yoke 46 engaging the chest intermediate the breasts.

It will be apparent that the ends 49 and 50 of the curved breast encircling portions 42 and 43 extend to the sides of the garment to extend the support of the pockets beyond what might be considered a truly circular or semi-circular contour. This braces and reinforces the support of the brassière at the sides of the body and aids in maintaining the garment firmly upon the body of the wearer and with the breasts in a raised and youthful position. The ends 33 and 34 actually extend to a point above the center of the pockets; whereas the ends 35 and 36 are substantially in alignment with the center of the pockets.

In the present construction, the member 41 is shown as composed of a strand or rod, preferably of metal, and having spring properties so as to substantially maintain a predetermined or desired shape, while, at the same time, being capable of yielding to compensate for breasts of different sizes. It will be understood, however, that the supporting and reinforcing member may be composed of any suitable material and shaped in any desired manner to adapt itself for the detachable mounting with such portions of a garment as encircle part of the breasts at the base of the breasts.

It will also be apparent that, with different types and kinds of brassières and other garments including breast pockets as an integral part thereof, such for example as slips, bathing suits and other garments, the pocket structures will be built into the garments. In other words, the garments will be joined by other body portions than simply the loops or bridge members 46, as well as the bands 20 and 21 and shoulder straps 16 and 17 in maintaining and supporting the pockets upon the body of the wearer.

The member 41 provides a unitary supporting frame structure in contrast to individual supporting frames employed in conjunction with each pocket, as is known in the art. Furthermore, the provision of pocket structures adapting the brace member or supporting frame for detachable mounting therewith to facilitate laundering of the garment constitutes another distinctive feature of the invention.

The loops 44 and 45 may be considered as coupling loops or other projecting elements which extend beyond the bridge member and are partially formed by extended ends of the curved portions 42 and 43. It is these coupling members which retain the supporting frame or yoke against displacement from the pockets, or the channel forming portions thereof. It will also be apparent that the ends 49 and 50 of the supporting frame extend outwardly from what would be the normal circular contour of the members 42 and 43. The purpose of this is to extend the support of the frame to the side seams, particularly at a point above lower ends of these seams, as is clearly illustrated in Fig. 1 of the drawing.

Having fully described my invention, what I claim as new and desire to secure by Letters Patent is:

1. In garments having breast pockets, means forming channels bordering portions of the periphery of the pockets, said means having openings adjacent and inwardly of ends of the channels at adjacent sides of the pockets, a unit breast supporting frame, said frame having end portions adapted for detachable mounting in the

channels of the pockets through said openings to reinforce the channelled portions of the pockets, a bridge member integrally joining and spacing said end portions centrally of the frame, and end portions of the frame joining the bridge member in loops fitting in the channels ends at adjacent sides of the pockets in retaining the pockets against displacement from the frame.

2. A brace member for breast pockets of garments of the kind defined, said member comprising curved end portions joined and integrally coupled by a U-shaped bridge part, the curved end portions of said end member adjacent the bridge part having projecting coupling loops, and said loops joining the bridge part in shoulder portions.

3. A brassière of the class described comprising a pair of breast supporting pockets, said pockets having side and back bands for supporting the brassière around the body of the wearer, each pocket having channels bordering edge portions of the pockets, the pockets having openings into said channels inwardly of and adjacent ends of the channels at inner sides of the pockets, a one-piece bracing member having end portions arranged in the channels of said pockets and detachable with respect to said channels through said openings, a bridge part integrally joining said end portions and spacing inner sides of the pockets, and said bridge part joining the end portions in loops arranged in the channel end adjacent said openings in retaining said member against displacement from said pockets.

4. In garments having breast pockets, means forming channels bordering portions of the periphery of the pockets, said means having openings adjacent and inwardly of ends of the channels at adjacent sides of the pockets, a pocket bracing member comprising curved end portions adapted for detachable mounting in the channels of said pockets through said openings, a U-shaped bridge part integrally joining and spacing adjacent ends of the curved portions of said member, and said bridge part forming of the adjacent ends of the curved portions extending coupling loops adapted to be mounted in said channel ends in retaining the pocket against displacement from the curved end portions of said member.

5. In garments having breast pockets, means forming channels bordering portions of the periphery of the pockets, said means having openings adjacent and inwardly of ends of the channels at adjacent sides of the pockets, a pocket bracing member comprising curved end portions adapted for detachable mounting in the channels of said pockets through said openings, a U-shaped bridge part integrally joining and spacing adjacent ends of the curved portions of said bridge, said bridge part forming of the adjacent ends of the curved portions extending coupling loops adapted to be mounted in said channel ends in retaining the pocket against displacement from the curved end portions of said member, and said bridge part comprising a reversely curved loop joining said coupling loops in shoulder portions and yieldably coupling the curved end portions.

6. The combination with brassières having independent breast covering pockets with means forming channels at predetermined bordering edges of the pockets, with the channels extending to and having openings at adjacent ends of the pockets inwardly of said channel ends, of a unitary bracing member for detachable mounting with respect to the channels of said pockets

through said openings in coupling said pockets together, said member comprising curved pocket supporting parts terminating in outwardly diverging end portions, a bridge part integrally joining and spacing adjacent ends of the first named parts in loop ends, and said loop ends extending into the channel ends in retaining the pockets against displacement from the curved pocket supporting parts of said member.

7. A brassière of the class described comprising a pair of breast supporting pockets, said pockets having side and back bands for supporting the brassière around the body of the wearer, each pocket having, at inner adjacent sides, a channel bordering the edge portion of the pocket, a one-piece brace member comprising channel engaging parts and a bridge portion integrally joining said parts, and said parts of the brace member and the channelled edge portions of the pockets having interengaging means retaining the pock-

ets against accidental displacement from said parts while permitting manually controlled attachment and detachment of the pockets with respect to said parts of the brace member.
